UNITED STATES PATENT OFFICE.

GEORGE ALEXANDER CARDWELL, OF NEW YORK, N. Y., ASSIGNOR TO
FREDERIC J. SWIFT, TRUSTEE, OF NEW YORK, N. Y.

PRINTING-TELEGRAPH RECEIVER.

SPECIFICATION forming part of Letters Patent No. 760,611, dated May 24, 1904.

Application filed April 11, 1903. Serial No. 152,202. (No model.)

To all whom it may concern:

Be it known that I, GEORGE ALEXANDER CARDWELL, a citizen of the United States, and a resident of the borough of Manhattan, city, county, and State of New York, have invented certain new and useful Improvements in Printing-Telegraph Receivers, of which the following is a specification accompanied by drawings.

10 My invention relates to printing-telegraph receivers of the class known as "page-printers;" and the objects of my invention are to improve upon the construction of such receivers, increase the rate of speed at which the machine may be worked, and produce an improved compact and strong instrument of high efficiency which is not liable to get out of order.

15 Another object of my invention is to increase the accuracy with which the printing and spacing are done.

20 Further objects will hereinafter appear; and to these ends my invention consists in apparatus for carrying out the above objects and embodying the features of construction, combinations of elements, and arrangements of parts having the general mode of operation substantially as hereinafter fully described and claimed in this specification, and shown in the accompanying drawings, in which—

25 Figure 1 is a side elevation, partly in section and partly broken away, of a machine embodying my invention. Fig. 2 is a rear elevation of the same with parts of the frame broken away. Fig. 3 is a plan view of the machine. Fig. 4 is a detail plan view on the line 1 1 of Fig. 1, showing the arrangement of the letter-selecting magnets. Fig. 5 is an enlarged detail longitudinal sectional view of the central hub or frame of the machine.

30 Fig. 6 is a plan view on the line 5 5 of Fig. 5. Fig. 7 is a detail sectional view taken through the type-wheel at upper portion of the central type-wheel shaft. Fig. 8 is a detail view, partly broken away, of a portion of the paper-carriage feeding and retracting mechanism. Fig. 9 is an enlarged detail view of the shaft and connecting parts for actuating the printing-hammer. Fig. 10 is a separate detail view, partly broken away, of the

winding mechanism for placing the central 50 vertical type-wheel shaft of the machine under a constant stress tending to rotate the same. Fig. 11 is an enlarged detail sectional view of a portion of the mechanism shown in Fig. 5. Fig. 12 is a view of the parts shown 55 in Fig. 11, but in a different position. Fig. 13 is a detail plan view of a portion of the mechanism shown in Fig. 12. Fig. 14 is a detail sectional view on the line 3 3 of Fig. 13. Fig. 15 is an enlarged detail sectional view of 60 the dash-pot for the paper-carriage. Fig. 16 is a detail front elevation of the paper-carriage. Fig. 17 is a transverse vertical sectional detail view on the line 4 4 of Fig. 16 looking in the direction of the arrow. Fig. 65 18 is a view similar to Fig. 17, but showing the parts in a different position. Fig. 19 is a transverse vertical sectional view on the line 5 5 of Fig. 16 looking in the direction of the arrow. Fig. 20 is a detail sectional view on 70 the line 6 6 of Fig. 16; and Fig. 21 is a view like Fig. 20, but showing the parts in a different position.

Referring to the drawings, upon a suitable base A is arranged a frame B, shown in this 75 instance as substantially circular, upon which are pivoted the levers C, controlled by the letter-selecting magnets D, shown as arranged in a circle about the frame B and adapted to attract the outer ends of the levers C and press 80 upwardly one at a time the pins E, which normally lie flush with the top of the plate F, but are adapted to be projected beyond the same to form stops for the arm G, secured to the central type-wheel shaft H and adapted to be 85 swept over the plate F, with the type-wheel shaft as a pivot.

The type-wheel I is secured to the central shaft H, shown in this instance as hollow and adapted to be placed under a constant stress 90 tending to rotate the same, the shaft and type-wheel I being held from rotation by the arm G and that pin E which is in a raised position. As the raised pin E is released and falls to its normal position flush with the top of the plate F another pin E is moved upwardly and the arm G is allowed to rotate through a portion of a revolution until again brought to a stop,

- thus affording means for selecting the desired letter on the type-wheel I and bringing said letter into position opposite the hammer J in order that printing may be effected.
- 5 Although any desired number of characters may be provided upon the type-wheel I, in this instance I have shown twenty-eight characters, and the wheel is controlled by twenty-eight letter-selecting magnets D. Suitable circuits and connections for controlling the operation of the said magnets and for controlling the various magnets utilized in my improved receiver may be provided, as hereinafter referred to.
- 15 Suitable means may be provided for placing the type-wheel shaft H, carrying the type-wheel I, under a constant stress, as shown in this instance a suitable magnet K, supported upon the frame of the machine, being arranged to wind a spring mechanism by a step-by-step motion. Each time that the magnet K is energized it attracts its armature a against the tension of the spring b and rotates the ratchet-wheel c, Fig. 10, by means of the pawl d', the stop-pawl e being provided to hold the ratchet-wheel in the position to which it is moved. Within the drum f, connected to the ratchet-wheel c, is a spring g, adapted to be wound up as the ratchet-wheel is rotated. The spring 30 g tends to rotate the gear-wheel h in an opposite direction to the movement of the ratchet-wheel c, a pinion i meshing with the gear h and also with another gear, j, at one end of a shaft k, which extends longitudinally of the machine. A bevel-gear l is secured to the other end of said shaft k and meshes with a bevel-gear o on the central vertical shaft H of the machine, whereby said shaft H is under a constant stress due to the spring g. Each 40 time that a letter is printed the winding-magnet K is energized, and the spring g is therefore kept in a constant state of tension.
- A central vertically-movable shaft L is arranged within the hollow type-wheel shaft H, and the type-wheel I is secured to said shaft L, the outer hollow shaft H being provided with a vertically-extending pin p, Fig. 7, passing through an aperture in the web of the type-wheel I, whereby rotation of the outer 45 hollow shaft H will cause rotation of the wheel I, which may or may not be fast to the central shaft L, in this instance the type-wheel being shown secured to the shaft L, as by means of a pin q.
- 55 The revoluble arm G is connected by any suitable means to rotate with the shaft H, and in Figs. 5, 11, 12, 13, and 14 the operation of the letter-selecting mechanism is illustrated on an enlarged scale. A supporting hub or 60 member O is provided centrally of the machine upon the base A and affords a support or bearing for the operative parts of the machine. This supporting member O is shouldered, as at r, and provided with a horizontal plate s, secured upon the shoulders r, as by

means of the screws t. Another plate u is arranged above the plates s and connected thereto by elastic means, as shown, a spring v, Fig. 6, being attached at one end to the upper movable plate u and at the other end to the lower fixed plate s, whereby the upper plate may have a slight rotary movement relatively to the lower plate. The plate F is shown as suitably secured to the central hub or member O, as by means of the screws w, and the pins E pass 75 through apertures in the plates s, u, and F and are adapted to be projected upwardly to extend beyond the upper surface of the plate e and form stops for the arm G. One pin is normally in a raised position, tending to hold the arm G from rotation, while the remainder of the pins are normally in a lowered position, and according to my invention the raised pin and all of the lowered pins are locked in such 80 position, means being provided for raising any one pin, as desired, and lowering that pin which is in a raised position and then again locking the pins. As shown in the drawings, the movable plate u is provided with apertures somewhat larger than the apertures in the 85 plates s and F, while the pins E are all provided with collars x, adapted to pass through the apertures in the plate u, suitable springs y being arranged upon each pin E between the plate F and the collars x, whereby each 90 pin is normally pressed into its lowermost position, with the collar x resting upon the lower plate s. The spring v, secured to both the plates u and s, is adjusted to maintain normally the apertures in the movable plate u out 95 of alinement with the collars x on those pins E which are in their lowermost position and also out of alinement with the collar x on that pin E which is in a raised position, so that the pins are all locked in position. As shown in the 100 drawings, the collars x are provided with upper beveled edges, so that when a letter-selecting magnet D is energized, thus attracting its armature C and pressing one of the pins E upwardly, the beveled edge of the collar x on the pin attracted bears against the inner edge of the aperture in the plate u over the collar x and tends to aline said aperture with the collar to permit the pin and collar to be raised through the aperture. In order 105 to vary the tension of the spring v and the relative positions of the plates u and s, another aperture z is provided in the upper plate u, and an eccentrically-mounted pin 1, secured to the lower plate s, projects into the aperture z 110 and is provided with a slotted head, whereby the position of said head may be changed relatively to the plate u to vary the tension of the spring v. In order to insure the alinement of the apertures in the plate u with the 115 collars x on the pins E, positive means are provided for accomplishing this end, although said positive means are auxiliary in their action and, if desired, need not be used. According to the construction shown a vertical 120

pin 2, Fig. 5, extends through the base of the machine and in this instance through the central hub O, the plate s, and the plate u and is provided with a beveled head 3, adapted to 5 a beveled or tapering aperture 4 in the movable plate u, said aperture 4 being set eccentrically to the head 3, whereby when the pin 2 is pressed downwardly the aperture 4 will be brought into alinement with the head of 10 the pin 2 and the plate u will be moved slightly against the tension of the spring v to bring the apertures in said plate in alinement above the collars x on the pins E to permit one of 15 said pins to be raised and another one to be lowered. A suitable coiled spring 5 normally tends to maintain the pin 2 in a raised position, while electromagnetic means are provided for pressing the pin downward.

As shown in the drawings, the magnet P, 20 which may be termed a "trip-magnet," is used for operating the pin 2, and when said magnet is energized its armature 6 is attracted against the tension of the spring 7 and a trip 8 is pressed against a collar 9 on the pin 2, 25 pulling said pin downward. The trip 8 is spring-pressed by a flat spring 10 and held normally in position to strike against the collar 9, and in order that sticking may not take place a stop 11 is provided, against which one 30 end of the trip 8 strikes at the end of the movement of the armature 6, rocking said trip upon its pivot 12, releasing the pin 2, which is then permitted to move upwardly again under the action of the spring 5.

According to my construction a printing-magnet is provided for printing from the type-wheel, and as its armature is attracted the printing takes place, while upon the back stroke of said armature a retracting-spring 40 for the paper-carriage is wound step by step and at the same time the inking-ribbon is fed step by step. Another magnet is utilized to release the paper-carriage spring to return the carriage for the beginning of a line.

As shown in the drawings, the magnet Q is termed a "printing-magnet" and is suitably supported upon the frame of the machine and arranged to control an armature 13, pivoted, as at 14, and pivotally connected at its 50 other end to the rod 15, extending transversely of the machine. The rod 15 is provided with a slot 16 and hung upon a pin 17, projecting from the arm 18, which is connected to the longitudinally-extending shaft 55 19, supported at one end in a bearing in a suitable bracket 20 and at the other end in the frame of the machine. As the armature 13 is attracted by the printing-magnet Q the rod 15 is moved longitudinally and the edge 60 of the slot 16, striking against the pin 17, rocks the arms 18 and the shaft 19 to actuate the printing-hammer J and cause it to strike against the paper and make an impression from the desired letter or character on the 65 type-wheel I.

Means are provided for yieldingly striking the hammer J against the type-wheel and for quickly retracting the hammer from the type-wheel after the printing has been done, and referring more particularly to Fig. 9, the collar 21 is fast to the shaft 19, and there is a sleeve 22 loose on said shaft and extending to the collar 21, but not connected thereto. The hammer J is fast on the sleeve 22, and a spring 23 is connected to the collar 21 and to the 70 hammer J, whereby when the shaft 19 is rotated to throw the hammer against the printing-wheel there will be a certain give to the hammer owing to the spring connection at 23. The collar 24 is fast to the shaft 19 and is connected with the frame of the machine by a spring 25. The shaft 19 also carries a stop 26, and there is a stop 27 fast to the sleeve 22, so that when the shaft 19 is rotated or rocked to cause the printing the stop 27 bears against 80 the stop 26 and both are carried in the same direction, the spring 25 being placed under a stress. When the hammer J is released after the operation of the printing, the tension of the spring 25 tends to rotate the shaft 19 and stop 26, together with the stop 27, thereby withdrawing the hammer J from the printing-wheel. As the rod 15 is moved longitudinally to cause the printing a pawl 28, pivoted to the end of said rod, moves past the teeth on the horizontal ratchet-wheel 29; but on the backward stroke of the rod 15 when the printing-magnet Q is deenergized the pawl 28 engages a tooth of the ratchet-wheel 29 and rotates said wheel to wind up the spring 30, Fig. 8, in 90 the drum 31. The ratchet-wheel 29 is loose upon the shaft 32 and connected to the clutch member 33, adapted to engage the clutch member 34, connected to wind up the spring 30. The spring-drum 31 is provided with a 100 gear 35, meshing with a rack 36 on the paper-carriage. Each time that the armature 13 of the printing-magnet Q is attracted the horizontal ratchet-wheel 29 is moved one step, the gear 35 is rotated, and the paper-carriage 105 fed forward one space for letter-spacing.

Suitable means are provided for throwing out the clutch 33 34 and thus permitting the paper-carriage to be returned under the influence of the spring-drum 31, as shown, a 110 carriage-return magnet R being arranged to control an armature 37, provided with a pin 38, adapted to the groove 39 in the clutch member 33, so that when said magnet R is energized, attracting its armature 37, the clutch member 33 will be separated from the clutch member 34 and the paper-carriage will be returned under the influence of the spring-drum 31. When the magnet R is deenergized, its armature 37 is retracted by a suitable spring 40, the tension of which may be adjusted by means of the adjusting-screws 41.

Means are provided for feeding the inking-ribbon 49 and thereby moving a fresh portion of the same opposite the type-wheel after 120 130

each impression, in this instance the feeding of the inking-ribbon being accomplished as the rod 15 is returned to normal position. A spring-pressed pawl 42 is pivoted upon said rod 15 and adapted to engage a ratchet-wheel 43 on a shaft 44, suitably supported from the frame of the machine and extending from side to side thereof. At each end of the shaft 44 are secured worm-wheels 45, meshing with gears 46 on vertically-extending shafts 47, to which are secured the rollers 48, over which the inking-ribbon 49 is rolled.

The paper-carriage P' is adapted to be moved from side to side of the machine and is provided with rods 50, adapted to slide on the rollers 51, suitably supported in the frame of the machine. The paper-carriage carries a roll of paper 52, which passes between the feed-roller 53 and the idle roller 54. Means are provided for feeding the paper for line-spacing, and according to my construction a paper-feeding magnet S, Fig. 3, is provided, controlling an armature 55, pivoted at its lower end and to which is pivotally attached a link 56, pivoted to a bent lever 57. The bent lever 57 is pivoted at 58 on the frame of the machine and extends over a bar 59, Fig. 16, vertically movable in suitable bearings on the paper-carriage and connected to actuate a vertically-movable rack 60, meshing with a pinion 61 on the shaft of the feed-roller 53. When the paper-feeding magnet is energized, attracting its armature, it will be seen that the rod 59 will be pressed downward and the pinion 61 will be rotated, connections being provided for rotating the feed-roller 53 to feed the paper a distance of a space between two lines. When the magnet S is deenergized and its armature is retracted, the rack 60 is permitted to rise under the influence of a suitable spring 62, and in this instance means are provided whereby the rack may move upwardly and rotate the pinion 61 in an opposite direction to that in which it was rotated before without rotating the feed-roller 53. The feed-roller 53 is loose upon the shaft 63 and has secured thereto a ratchet-wheel 64, while an arm 65 is fast upon the shaft 63 and is provided with a pawl 66, adapted to coöperate with the ratchet-wheel 64 and rotate the same, thereby rotating the feed-roller when the rack 60 is moved downward. A suitable stop-pawl 67 is provided for coöoperating with the ratchet-wheel 64. According to this construction it will be seen that the rack may move upward without rotating the feed-roller 53. It is very desirable to prevent the paper being fed more than the desired space for one line, and according to my invention means are provided for preventing the paper from being fed beyond the distance of one space at a time, as shown, a stop-pawl 68 being provided in this instance at the opposite end of the paper-carriage from that in which the rack is located. The stop-pawl 68 is nor-

mally spring-pressed out of engagement with the ratchet-wheel 64, fast to the feed-roller 53 at that end of the paper-carriage; but as the shaft 59 is pressed downward it will be seen that the parts are so arranged that the stop-pawl 68 will be pressed into position to coöperate with the teeth on the ratchet-wheel 64', whereby said ratchet-wheel may not be moved beyond a certain distance, and according to my construction the feed-roller may not be rotated through a greater distance than that between two teeth on the ratchet-wheel 64'. The remainder of the construction at the opposite end of the paper-carriage is similar to that already described for the end at 70 which the rack is located and is shown in detail in Figs. 20 and 21.

If desired, means may be provided for locking the printing-wheel in a given position while printing is being done, as shown in this instance, said locking means being actuated by the movement of the longitudinally-movable rod 15, actuated by the printing-magnet Q. As the arm 18 is rocked with the shaft 19, another arm, 69, is rocked, and connections are 80 provided for moving a pawl 70 into engagement with the ratchet-wheel 71, fast to the revolute vertical shaft H.

In order to prevent jarring and derangement of the parts when the paper-carriage is returned, I provide a dash-pot 72 for the paper-carriage. The plunger 73 is movable within the dash-pot 72, and a spring-pressed piston or plunger rod 74 is connected to the paper-carriage, whereby when the paper-carriage is retracted the plunger-rod 74 impinges against the plunger 73, and the carriage is cushioned by the dash-pot 72. As shown, the plunger 73 is not connected to the plunger-rod 74, and means are provided for withdrawing the plunger from the bottom of the dash-pot as the paper-carriage is fed forward, in this instance the plunger being made hollow and provided with an inwardly-extending flange 75, with which a hook 76 on the plunger-rod 74 is adapted to coöperate. As the rod 74 moves into the dash-pot 72 it rides upon a projection 77, raising the hook 76, so that when the carriage is fed forward the hook engages the flange 75 and withdraws the plunger. 115

According to my construction the type-wheel I is provided with two sets of type or characters, an upper and a lower set, from either of which the printing may be effected, as desired. In order to be able to print from either set of type on the wheel, provision is afforded for raising and lowering the type-wheel to bring either set of type opposite the printing-hammer J. In this instance the inner shaft L is vertically movable, and means are provided for moving it vertically to bring either set of type into position for printing. In the position of the parts shown in Fig. 1 the lower set of type is in position for printing, as shown, the vertical shaft L resting 125

upon the arm 78, extending from the armature 79, controlled by the type-wheel-lifting magnet T. The armature 79 is held in position to maintain the shaft L raised by suitable means (shown as a latch 80) upon the armature 81, pivoted at 83 and adapted to be attracted by the releasing-magnet U against the tension of the spring 82. When the magnet U is energized, it attracts its armature 81, thus raising the latch 80 and releasing the armature 79, which permits the shaft L to move downward by reason of its own weight and bring the upper set of type opposite the printing-hammer J. The adjustable stops 84 limit the downward movement of the arm 78 and permit the extent of movement of the shaft L to be adjusted. In order to raise the type-wheel again, the magnet T is energized, attracting its armature 79 and raising the shaft L. Then the magnet U is deenergized, and the latch 80 falls into position and maintains the armature 79 in a raised position after the type-wheel-lifting magnet T has become deenergized.

Suitable means are provided for spacing without printing, and for this purpose a lock is provided for preventing the printing-hammer from striking the type-wheel when desired and for as long a time as desired, so that the requisite spacing may be effected without printing. I have shown a magnet V, controlling an armature 85, pivoted at 86 and normally retracted by a spring 87. When the spacing-magnet V is energized, its armature 85 is attracted and a latch 88 moved into position to coöperate with a stop 89 on the printing-hammer J to prevent the hammer from being actuated to effect printing. The latch 88 is held against a stop 90 on a bracket projecting from the frame of the machine and effectually prevents the operation of the printing-hammer. The latch 88 is restored to its normal position to permit printing to be effected by being removed from engagement with the stops 89 and 90.

Any suitable circuits and connections may be provided for operating my improved printing-telegraph receiver, for it will be obvious to those skilled in the art that various different arrangements of circuits may be devised for effecting the operation and control of the apparatus in the desired manner.

If desired, the circuits and apparatus fully disclosed in my United States Patent No. 673,815, granted April 30, 1901, may be utilized in connection with my present invention. In the apparatus shown and described in that patent a distinctive series of electrical impulses is employed for effecting the printing of each letter or character, and according to my present invention such a distinctive series of electrical impulses may be provided for controlling each letter-selecting magnet D and also for controlling each remaining operating-magnet of the receiver. The electric

connections, however, form no part of my present invention and need not be further referred to, especially since the method of operation shown and described in my former patent referred to is but one of many methods of operating my improved receiver.

To recapitulate the operation of the apparatus, it will be assumed that the parts of the receiver are in the position shown in the drawings, with the type-wheel in readiness to print from the lower set of letters or characters. The paper letter-selecting magnet D is energized by any suitable means, while at the same time the arm G is released and moved against the stop E of the magnet energized, which brings the required letter or character opposite the printing-hammer J. The printing-magnet Q is then energized, and the hammer J is actuated to effect the printing through the mechanism hereinbefore fully described. On the back stroke of the armature a of the printing-magnet Q the paper-carriage is fed forward one step for letter-spacing, and the inking-ribbon is fed to bring a fresh portion thereof opposite the printing-hammer or platen. It will be observed that as the paper-carriage is fed forward for letter-spacing its retracted spring 30 is being wound up step by step in readiness for retracting the carriage when desired. The operations above described are continued until it is desired to begin a new line, in which case the carriage-return magnet R is energized, and the clutch restraining the paper-carriage is disengaged to permit the return of the carriage under the influence of the spring. For line-spacing the paper-feeding magnet is energized, and the paper is fed the space of one line, as hereinbefore fully described. Each time that a magnet D is energized the pin trip-magnet P should be energized in order, as stated, to insure a positive movement of the plate u to permit the pins E to move freely. The winding-magnet K may be suitably controlled by keeping the spring g on a tension. If it is desired to effect spacing along a line without printing, the spacing-magnet V is energized to prevent the operation of the printing-hammer until printing is to be effected again. The printing from either the upper or lower set of letters or characters on the type-wheel is controlled, as described, by the type-wheel-lifting magnet T and the releasing-magnet U.

Obviously some features of my invention may be used without others, and my invention may be embodied in widely-varying forms.

Therefore, without limiting myself to the construction shown and described nor enumerating equivalents, I claim, and desire to obtain by Letters Patent, the following:

1. In a printing-telegraph receiver, the combination of a rotary type-wheel shaft and type-wheel, an arm extending from said shaft and rotatable therewith, a series of stops movable into and out of the path of rotation of

6
said arm, electromagnets for actuating said stops, and means for locking all of said stops from operation including the one actuated after one has been actuated, for substantially 5 the purposes set forth.

2. In a printing-telegraph receiver, the combination of a rotary type-wheel shaft and type-wheel, an arm extending from said shaft and rotatable therewith, stops movable into 10 and out of the path of rotation of said arm, electromagnets for actuating said stops, and means for locking the remainder of the stops after one has been actuated, for substantially 15 the purposes set forth.

3. In a printing-telegraph receiver, the combination of a rotary type-wheel shaft and type-wheel, an arm extending from said shaft and rotatable therewith, stops movable into 20 and out of the path of rotation of said arm, electromagnets for actuating said stops, means for locking the remainder of the stops after one has been actuated, and means independent 25 of the stops for releasing all of them at once, for substantially the purposes set forth.

4. In a printing-telegraph receiver, the combination with a rotary type-wheel shaft and type-wheel, an arm extending from said shaft and rotatable therewith, stops movable into 30 and out of the path of rotation of said arm, electromagnets for positively projecting the stops forward into the path of rotation of said arm, and means for locking the remainder of the stops and also the stop projected forward, for substantially 35 the purposes set forth.

5. In a printing-telegraph receiver, the combination of a centrally-arranged rotary type-wheel shaft and type-wheel, an arm connected to rotate the said shaft, a stationary disk or 40 plate, pins or stops passing through said disk or plate and guided thereby, collars on said pins, means for actuating said pins, and another disk or plate adapted to be moved relatively to the stationary plate to lock said pins, for substantially 45 the purposes set forth.

6. In a printing-telegraph receiver, the combination of a rotary type-wheel shaft and type-wheel, an arm connected to move with said shaft, stationary and movable disks or plates, a series of stops passing through said plates 50 and adapted to be projected into the path of movement of said arm, and collars on said stops, whereby the stops may be locked by the movable plate, for substantially the purposes set forth.

7. In a printing-telegraph receiver, the combination with a type-wheel and shaft and a hammer or platen, of means for actuating the platen, and means for actuating the type-wheel shaft, and an electromagnet for preventing 60 the operation of the hammer to permit spacing without printing, for substantially the purposes set forth.

8. In a printing-telegraph receiver, the combination of a type-wheel shaft and type-wheel, 65 printing mechanism, a printing-magnet and

operative connections for actuating the printing mechanism as the magnet is energized, a paper-carriage and a retracting-spring therefor, and means for winding said spring as the printing-magnet is deenergized, for substantially 70 the purposes set forth.

9. In a printing-telegraph receiver, the combination of a type-wheel shaft and type-wheel, printing mechanism, a printing-magnet, a pivoted armature and paper-carriage, a retracting-spring therefor, a rod pivotally connected at one end to said armature and connected to 75 actuate the printing mechanism as the magnet is energized, a ratchet-wheel connected to wind the paper-carriage spring, and a pawl on said rod arranged to actuate the ratchet-wheel as the armature of the printing-magnet is retracted, for substantially the purposes set forth. 80

10. In a printing-telegraph receiver, the combination of a type-wheel shaft and type-wheel, printing mechanism, a printing-magnet, and operative connections for actuating the printing mechanism as the magnet is energized, a paper-carriage and a retracting-spring therefor, an inking-ribbon, and means for winding said spring and for feeding said inking-ribbon as the printing-magnet is deenergized, for substantially 90 the purposes set forth. 95

11. In a printing-telegraph receiver, the combination of a type-wheel shaft and type-wheel, printing mechanism, a printing-magnet and operative connections for actuating the printing mechanism as the magnet is energized, a paper-carriage and a retracting-spring therefor, means for winding said spring as the printing-magnet is deenergized, and an independent magnet for releasing said spring to retract the paper-carriage, for substantially 100 the purposes set forth. 105

12. In a printing-telegraph receiver, the combination with a paper-carriage and means for retracting the same, of a dash-pot, a plunger movable therein, and a plunger-rod connected to move with the paper-carriage and loosely connected to the plunger, said plunger-rod being constructed to move the plunger outward in the dash-pot, upon the outward movement of the paper-carriage, for 110 substantially the purposes set forth. 115

13. In a printing-telegraph receiver, the combination with a paper-carriage and means for retracting the same, of a dash-pot, a plunger movable therein, and a spring-pressed plunger-rod pivotally connected to the paper-carriage and adapted to engage the plunger upon the outward movement of the plunger-rod, whereby said dash-pot and plunger cushion the paper-carriage each time it is retracted, for substantially the purposes set forth. 120 125

14. In a printing-telegraph receiver, the combination of a paper-carriage having a vertically-movable bar, rollers for holding the paper, a paper-feeding magnet and armature, 130

a pivoted bent lever connected to be actuated vertically by said armature, the lever extending over the bar on the paper-carriage, operative connections between the said bar and the rollers for feeding the paper, and devices actuated by said bent lever and bar for preventing the paper from being fed more than the desired space for one line, for substantially the purposes set forth.

10 15. In a printing-telegraph receiver, the combination of a revoluble sleeve and a shaft loose therein, a type-wheel on said shaft having a plurality of sets of characters, provision being afforded for connecting the wheel 15 to rotate with the sleeve, a platen, an electro-

magnet for moving the shaft longitudinally, and a locking-magnet with connections for locking the shaft in the desired longitudinal position to bring either set of characters of the type-wheel into operative relation with the platen, for substantially the purposes set forth.

In testimony whereof I have signed this specification in the presence of two subscribing witnesses.

GEORGE ALEXANDER CARDWELL.

Witnesses:

E. VAN ZANDT,
A. L. O'BRIEN.
